Primary Examiner — Sharon S Oum(74) *Attorney, Agent, or Firm* — D'Ambrosio & Menon, PLLC; Usha Menon(57) **CLAIM**

The ornamental design for a wind turbine, as shown and described.

DESCRIPTION

FIG. 1 is an isometric view of a wind turbine, showing my new design;

FIG. 2 is a top view thereof;

FIG. 3 is a bottom view thereof;

FIG. 4 is a side view thereof; and,

FIG. 5 is a partial exploded view thereof.

The broken line in the figures represent environmental structure and form no part of the claimed design.

1 Claim, 5 Drawing Sheets(56)
